EXTENDED FIN SURFACE FOR CONDUITS

James Forrest Cobb, Portland, Oreg., assignor to
Moore Dry Kiln Company of Oregon, a corpora-
tion

Application January 19, 1932, Serial No. 587,536

16 Claims. (Cl. 257—262)

My invention relates to improvements in fins for pipes or conduits and has for its main object the production of a novel fin and novel means for superimposing it on pipes or conduits containing a heating or a cooling fluid.

An object of my invention is to provide a removable fin with resilient means which will give sustained intimate contact with a pipe or conduit.

Another object of my invention is to provide a novel design of shape which will transmit heat efficiently from a fluid within the conduit to the atmosphere surrounding the conduit, or from the atmosphere to a fluid within the conduit.

Another object of my invention is to provide a single unit of annular shape which I call a fin, for a conduit which fin will nest with another fin at either of its sides, in assemblage on a conduit, whereby heat transmission between a surrounding atmosphere and a fluid within the conduit is promoted.

Another object of my invention is to provide a fin having an extended annular flanged surface for a fluid containing conduit, and having a partite medial section comprising individually resilient fingers spaced around a medial opening, the fingers maintaining intimate contact with the conduit regardless of expansion or contraction due to heating or cooling of the fins or the conduit.

Another object of my invention is to provide a fin for a conduit more efficient for heat transfer, between the conduit and the fin because of their having greater and better surface contact.

Other objects of my invention will be made apparent to one skilled in the art from the following specification:

What constitutes my invention will be herein-after described in detail and succinctly defined in the appended claims.

In the accompanying drawing wherein I illustrate my invention in present preferred form of embodiment,

Figure I is a plan view of a fin viewed from one of its faces;

Figure II is a cross section along the line II—II of Figure I;

Figure III is a side elevation of an assemblage of fins, illustrated in Figure I, mounted on a pipe.

Figure IV is a partial plan view of one of my fins illustrating certain features of its construction.

Figure V is a horizontal cross section of a plurality of vertical conduits having a fin common to all of them superimposed thereon.

Figure VI is a vertical section along the line VI—VI, of Figure V, also showing a common supply header.

Referring to the numerals on the drawing—1 indicates a fin, made preferably from a piece of resilient sheet metal, a number of which fins may be superimposed in series on a conduit 2 as illustrated in Figure III.

Attention is called to the shape of the fin 1 illustrated in Figure II, which is a preferred form. By means of a stamping process an intermediate portion of a sheet metal plate dished at 10 on one face, lies between a preferably flat outer flange 5 and a partite medial section having fingers 3 formed around the periphery of a medial opening 4 of the fin 1, and projecting laterally from one of its faces, the inner surfaces of said fingers converging for example, along the lines 13.

The fin is preferably made from metallic sheet having high resilience, and conductivity. The resilience or elasticity is an essential characteristic of the fingers 3.

The intermediate portion 10 of the fin is dished on one of its faces, or otherwise shaped in any manner preferable to render the outer flange surface 5 of the fin 1 relatively inflexible. This is accomplished by annular bends, for example, at 8 and 9 which are respectively preferably uniformly spaced from the outside periphery of the fin 1 when it is substantially round as illustrated in the drawing. These bends produce in effect a corrugation in the surface of each side of the fin.

It is understood that the fins may be of any desired shape. They are illustrated as being substantially round, but they may be made substantially square, hexagonal, elliptical, or any desired peripheral shape. It is understood also that the shape of the fin may be individually varied as desired.

The fingers 3 are illustrated as forming lateral extensions from preferably one face of the fin, their inner surfaces converging, before being superimposed on the conduit. In Figures I and IV the inner surfaces 15 of the fingers are shown rounded to fit the round external surface of a pipe for example. It is understood that similar fingers may be made to conform to the outside surface of a square or rectangular conduit. The conduit may be of any preferred shape in cross section, such as round, elliptical, or having parallel sides.

Attention is called to the slits 12 between fingers. These slits, spaced at intervals, preferably extend laterally or radially as illustrated in Figure

I from the medial opening 4 beyond the point of contact of the fingers 3 with the conduit, and preferably extend across a flat surface 14 of the fin, the plane of which surface is shown, for example, at substantial right angles to the conduit. However, this angle is immaterial.

Before the fin is assembled on a conduit the laterally extending fingers 3 in Figure II have their inner surfaces converging, illustrated by the numeral 13 designating the median lines of said surfaces of opposite fingers. In other words, the distance between the tips 6 of opposite fingers is less than the distance between their inner surfaces 7, which have preferably substantially the same radius 18 of inner curvature as the outer surface of the conduit. This convergence makes it possible to spring the fingers outwardly within their elastic limit so that these median lines 13 will be substantially parallel to each other when the fins are assembled on a conduit as shown in Figure III. The resilience of the fingers permits their springing, and causes them to grip the surface of the conduit along their inner surface extending from 6 to 7 on the finger with sustained pressure, thus permitting large contacting areas and greater heat transfer between the fin and the conduit.

The individual substantially flat base 14 for each finger is an essential feature of my invention, its function being to provide greater individual spring action of the fingers 3 at the base of each, whereby the laterally extending inner surface of each finger of the fin will more firmly grip the pipe or conduit 2. The slits are preferably made by shearing the surface of the plate between fingers and bending their inner ends laterally to form the fin shown in Figure I. The slits tend to open when the fins are assembled on a conduit, due to the springing of the fingers outwardly to permit their inner surfaces to contact the conduit surface. Attention is called in Figure IV to the trapeziform shaded area which is shown for purposes of illustration only, as defining the base 14 of each finger 3. This shaded area defines a substantially flat area of the fin which is free to flex within the elastic limit of the material used in the finger, thus facilitating assembly of fins on the conduit making it possible to maintain greater pressure of the fingers against the conduit and therefore greater conduction of heat between the fin fingers and the conduit. This trapeziform area is bounded by the slits 12 and imaginary lines drawn across the flat surface parallel to a line tangential to the conduit.

It is understood that the flat surface 14 may be of any size or shape, the main object of it being to provide greater elasticity of the fingers. When highly resilient metal is used to form the fins the flat surface 14 may be reduced to a narrow area extending transversely across the base of each finger between the slits 12, which will, as an axis of flexion, give the necessary elasticity and resilience to the fingers.

When the circular fins are nested on a pipe as illustrated in Figure III, a triangular space 17 is provided between the fingers leaving the conduit surface exposed therethrough, providing direct heat transfer between the surface of the conduit and the surrounding atmosphere.

It is understood that in case the conduit 2 is rectangular in cross section, the slits 12 of some of the formed fingers may be parallel to each other, or not, as desired. In this case or in the case of the circular fin illustrated, resilient fingers

are essential. The flat surface area gives resiliency to the fingers.

Attention is called to Figure III which is a view of three juxtaposed fins assembled on a pipe 2. In this position the tips 6 of one fin set firmly against the outer surface of the bend 16 of another fin.

As shown in Figures IV and VI in some embodiments of my invention the tips of the fingers 3 may be made wedge shaped in median section 10 as shown at 11, if desired to fit against the outer surface of the bends 16 to give greater contact between fins.

By superimposing and welding one fin on a conduit, and by superimposing and jamming successively, additional fins in a nested arrangement, a tight assemblage of the fins on the conduit 2 is provided, and therefore a more efficient transfer of heat between the fins and the conduit is made possible. The last fin or fins on any one conduit 20 may also be welded to the conduit.

In the assemblage, the ends of the fingers of one fin are preferably wedged against the bend 16 of the fin ahead of it. The resilience of the fingers being augmented by the wedged assembly 25 of the fins to give greater contact between the fins and the conduit. This wedging, illustrated in Figure VI, is effected in the assemblage of fins as they are pressed on a conduit. The tips 6 of the fingers 3 are jammed into the wedge shaped 30 space between the surface of the conduit and the outer surface of the bend 16 of the adjacent fin. The tips may be wedge shaped as illustrated at 11 in Figures IV and VI or they may be blunt as in Figure II. In juxtaposed assemblage the 35 outer surface of the rounding bend 16 holds the tip of the fin in the wedge shaped space provided thereby, firmly against the conduit.

In the process of heating and cooling, the conduit and the fins will expand and contract. The 40 individual resiliency of the fingers makes it possible for the fin to maintain a sustained gripping contact with the conduit regardless of expansion and subsequent contraction.

The slits define two sides of the base of each 45 finger and make possible the required resiliency, which is an essential feature of my invention.

The tight assemblage of the fins on the conduit does not impair the individual resiliency of each 50 of the fingers, which permits them to maintain a sustained contact pressure on the conduit regardless, for example, of variable pipe size which is characteristic of commercial pipe, or changes in its size, caused by temperature changes of the 55 fluid therein.

These fins may be used to increase the heating effect of conduits wherein a hot fluid is carried within the conduit and which heats the conduit wall by conduction; the pipe wall in turn heats the fin fingers by conduction and the fin itself by conduction and radiation; and the fins in turn heat atmosphere surrounding them by conduction and radiation.

The fins may be placed at any preferred 65 interval on the conduit. They may be dished or bell shaped, they may be made in halves, or they may be made for attachment to two or more conduits, as illustrated in Figures V and VI, the resiliency of the fingers always remaining an 70 important feature.

The fins may be made of copper, aluminum, steel or any other suitable material and their thickness may vary to suit the heat transfer conditions of the material that is used.

These fins are also useful for a piping system used for cooling as well as for heating.

When preferred the fins may be made in halves or any number of parts and welded or otherwise joined together for assembly on the conduit. In this case the assembled fins on the conduit would have fingers in substantially the same relationship to the conduit as illustrated in Figures I, II and IV. The same individual resiliency of the fingers of the assembled fin would be present and exert a sustained pressure by surface contact with the conduit, as if the fin were made as a unit as shown in Figures I and II.

In some cases I prefer to make a number of fingered openings in one strip of metal or other suitable material to be used as a common fin for a plurality of conduits which are connected to a common header 20, having a supply pipe 21. In this case the extended surface may be substantially as illustrated in Figures V and VI.

It is understood that this invention is not limited to the exact design and form illustrated and described. Modifications of the principles herein described are self-evident to those skilled in the art; therefore, it is to be understood that the invention includes within its scope whatever changes fairly come within either the terms or the spirit of the appended claims.

What is claimed is:—

30 1. A fin having an extended, annular, plate surface, for a fluid containing conduit, a medial opening in said fin, a plurality of fingers extending laterally from one of its faces and distributed peripherally around said medial opening through 35 which the conduit is inserted, the said fingers having surfaces in contact with the outside surface of said conduit, said fingers having a tendency to converge inwardly, and each of said fingers having a resilient base area consisting of a 40 portion of the plate with slits on two sides whereby sustained contact pressure is exerted by said fingers against the surface of said conduit.

2. A fin providing an extended surface for a conduit, said fin comprising an annular laterally extending plate with an opening centrally disposed therein, said opening having around its periphery a series of fingers projecting laterally from one of the faces of said fin, the inner surfaces of said fingers converging, each finger being 50 separated from the adjoining fingers by a slit extending from the end of the finger across a substantially flat area of the plate, the area between two slits comprising a base for one finger, said base being resilient whereby greater resiliency is provided in each finger.

3. In a fin providing an extended surface for a conduit, the combination of an annular dished laterally extending plate, a series of fingers, the ends of which have inner surfaces tending to 60 converge and extending laterally from one of its faces around the periphery of a centrally disposed opening therein, each finger being integral with a resilient base area of said plate which is bounded on each of two sides by a slit, whereby each finger individually has gripping contact on one of its surfaces with the outside surface of said conduit providing greater heat transfer between said conduit and the atmosphere surrounding said fin.

70 4. In a fluid containing conduit, the combination therewith of a fin formed of an extended, annular plate, a partite medial section thereof comprising laterally extending fingers with inner surfaces in contact with the surface of said conduit, said plate having a resilient base area for

each of said fingers, each separated from the next adjacent base areas by slits, each base area being in tension on the side of the finger adjacent to the conduit, and in compression on the side of the finger away from the conduit, whereby individual sustained contact pressure is maintained by each of said fingers against the surface of the conduit regardless of changes in the size of the fin or the conduit due to expansion and contraction.

5 5. In a fin, an extended annular plate having a medial opening for a substantially round fluid containing pipe, fingers extending substantially perpendicularly from said plate and distributed around the medial opening, said plate including 15 a resilient base portion for each of said fingers, each base portion lying between two slits in the plate, the inner surfaces of each of said fingers being rounded to fit the outside surface of the pipe, and said fingers having a tendency to converge inwardly to maintain gripping contact with said pipe under the influence of said resilient base portions.

6. A fin, formed of an extended annular plate, said fin having a partite medial section with an 25 opening therein for a conduit, said medial section comprising fingers integral with and extending substantially perpendicularly from said plate to make surface contact with said conduit, said 30 plates comprising individual, planiform resilient base portions for said fingers, and slits bounding two sides of each of said base portions, whereby said fingers maintain gripping surface contact with the surface of said conduit.

7. A series of fins, comprising laterally extended annular flanged plates for a fluid containing conduit, each having a dished partite medial section comprising fingers, medially bent outwardly around a medial opening, each of said 40 fingers having a resilient base portion, the ends 45 of said fingers converging to bring the end of each finger into close contact with the outer surface of the conduit.

8. On a conduit the combination of a series of juxtaposed fins, each fin comprising a dished flanged surface, said fins each having a partite medial section comprising laterally extending fingers curved on their inner surfaces to fit the surface of said conduit, said flanged surface comprising substantially flat base areas having slits 50 on two sides which extend between said fingers, each finger being in tension on its surface adjacent to the conduit and in compression on the surface away from the conduit, whereby greater sustained contact pressure is effected by said 55 fingers against the surface of the conduit.

9. In a heater, the combination of a conduit, a series of fins superimposed on said conduit, said fins each having a plate extending laterally from said conduit and individually resilient fingers having surface contact with the surface of said conduit, said plate being slotted to form a plurality of substantially flat base areas each bounded on two sides by slits, each area being integral with one of said fingers, each of said 65 fingers having a wedge shaped tip, a bend between the base area and the end of each finger, said bend providing a wedge shaped space between the outer surface of the bend and the conduit, whereby the tip of the finger of an adjacent fin may be jammed into said space and held against said conduit.

10. A radiator fin comprising a plate and a plurality of individual laterally extending fingers around a medial opening therein, said plate com- 75

prising a resilient base area integral with each finger and defined on two sides by slits.

11. A radiator fin comprising a dished plate, and a plurality of individual laterally extending 5 wedge tipped fingers around a medial opening therein, said plate comprising a substantially flat base area integral with each finger and defined on two sides by slits.

12. A radiating fin adapted to grip a pipe by 10 spring action, defined as a plate provided with a central opening therein, the said opening being bounded by a plurality of spring fingers slitted from the plate on lines that radiate from the central part thereof and bent outwardly, each 15 finger being joined to the main plate by a slit defined base area that is integral with the plate and the finger.

13. A radiating fin for a pipe, formed by dishing the center of a plate, placing radial slits in 20 the dished portion that intersect in the center to define fingers and medially bending the fingers normal to the plate to delimit a pipe opening surrounded by short finger points, each provided with a slit defined spring base area.

25 14. A fin for a pipe, comprising in unitary

structure a plate provided with a central dished area, intersecting radial slits in the dished area to define a plurality of fingers, the points of which are bent outwardly, normal to the plate, to define an opening for a pipe, with each finger thus provided with a slit defined unbent spring base area.

15. A pipe fin defined as a plate provided with intersecting radial slits formed in a centrally disposed area to define a plurality of slit defined 19 spring fingers, the said fingers being medially bent outwardly to a plane normal to the plane of the plate, to form a pipe opening surrounded by the spring fingers.

16. A radiating fin defined as a plate provided with a plurality of radial slits that intersect at the center to define fingers which terminate short of the outer boundary of the plate, the said fingers being bent outwardly to define a circular pipe opening, at a point short of the determinant 20 ends of the slits to define a base area that acts as a spring support for the finger of which it forms an integral part.

JAMES FORREST COBB. 25
